DESIGN FOR A HAT

Samuel Scheuer, New York, N. Y.

Application March 30, 1937, Serial No. 68,480

Term of patent 3½ years

To all whom it may concern:

Be it known that I, Samuel Scheuer, a citizen of the United States of America, residing in city of New York, county of New York, and State of New York, have invented a new, original, and ornamental Design for a Hat, of which the following is a specification, reference being had to the accompanying drawing, forming part thereof.

Fig. 1 is a front perspective view of a hat showing my new design.

Fig. 2 is a side view in perspective thereof.

The appearance of the hat from the rear is conventional, as indicated in Fig. 2. Said hat comprises a stitched visor portion and an unstitched back portion having lateral extensions which meet in the opening on the visor in a bow as shown.

I claim:

The ornamental design for a hat substantially as shown and described.

SAMUEL SCHEUER.
